SAFETY DEVICE FOR FLUID FUEL BURNERS

Carl G. Kronmiller, Minneapolis, Minn., assignor
to Minneapolis-Honeywell Regulator Company,
Minneapolis, Minn., a corporation of Delaware

Application June 27, 1936, Serial No. 87,706

27 Claims. (Cl. 158—117.1)

1

My invention relates to control apparatus and more particularly to control apparatus designed for use in a fuel burner control system.

In fluid fuel burner control systems employing a constantly burning pilot for igniting the fuel supply to the main burner, it is customary to employ an arrangement generally designated as a safety pilot which is effective to prevent fuel from being supplied to the burner unless the pilot burner is lit. The safety pilot arrangement may either take the form of a valve in the main fuel line and apparatus for insuring that the valve is closed if the pilot burner is not ignited or of apparatus associated with the main shut-off valve to insure that the same will be in closed position when the pilot is extinguished. Due to the fact that the extinguishment of the pilot is often due to conditions which should be corrected before the system is again placed in operation, it is desirable in many instances to so arrange the safety pilot mechanism that it is necessary for a manual operation to be performed in addition to re-lighting of the pilot in order for the system to again be placed into operation. In the case of the first type of safety pilot mechanism mentioned above which comprises a separate valve in control of the main fuel line, such mechanism commonly takes the form of some means for opening the valve and holding it open until a member responsive to the presence of a flame at the pilot burner is effective to hold it in this position when the manual means is released. With such prior apparatus, however, it was possible when the main control valve was open to admit gas each time the safety pilot valve was opened by the manual operating arrangement. In other words, what would happen would be that the operator would open the safety pilot valve permitting a certain amount of gas to issue from the burner and would then discover that the pilot burner was not ignited and would release the manual means permitting the valve to close. In the mean time, however, a large amount of gas would have escaped from the burner and by reason of the pilot being extinguished would not be re-ignited. Upon the subsequent lighting of the pilot, the unignited gas would be suddenly ignited with explosive violence.

The object of the present invention is to provide in apparatus of the general type previously discussed, an arrangement wherein it is impossible to even momentarily permit fuel to be supplied to the burner through manual operation of the resetting device, if the pilot is not ignited.

A further object of the present invention is

5 to provide in such safety pilot apparatus an arrangement whereby it is impossible to interrupt the supply of fuel to the burner by accidental operation of the resetting device when the pilot is burning.

10 A further object of the present invention is to provide an arrangement of this type wherein a magnet controlled by a thermo-couple responsive to the pilot flame is the means effective to hold the valve in open position.

15 A further object of the present invention is to provide a new and novel arrangement for actuating a holding element in a safety pilot arrangement, employing a flexible connecting member housed in the tube as a medium for imparting movement from an element responsive to the presence or absence of a flame at the pilot burner to a holding means which is effective to hold the fuel control device in a position permitting the 20 flow of fuel.

25 Other objects of the present invention will be apparent from consideration of the accompanying specification, claims and drawing, of which,

Figure 1 is a schematic view of a portion of 30 a burner control system employing the novel controlling mechanism of the present invention;

Figure 2 is a view partly in section of the valve portion of a preferred form of the invention, with the valve in closed position;

Figure 3 is a sectional view taken along the line 3—3 of Figure 2 and in the direction of the arrows adjacent said drawing;

Figure 4 is a view of the valve mechanism at an intermediate stage of the resetting process;

Figure 5 is a view of a portion of the valve with the valve in open position;

Figure 6 is a view of a pilot burner and a thermostatic arrangement employed therein for controlling a holding device employed with the valve;

Figure 7 is a detail view of a portion of the apparatus shown in Figure 6;

Figure 8 is a schematic view of a burner control system employing a modified form of my controlling mechanism;

45 Figure 9 is a view in section of the modified form of the controlling mechanism of the present invention;

Figure 10 is a detail view of a portion of the electromagnet employed in the structure of Figure 9.

Referring to Figure 1 of the drawing, a gas burner which may be of any conventional type is designated by the reference numeral 10. Connected to the burner 10 is a pipe 11 which is connected to a gas main and serves to supply fuel

to the burner. Interposed in the fuel line 11 is a main control valve designated by the reference numeral 12. This valve may be of any desired type. In an automatic system this valve may, for example, be of the type driven by an electric motor, the motor of which is controlled by a room thermostat or similar device. The particular form of this valve plays no part whatsoever in the present invention.

Also interposed in the fuel line 11 is a valve 13 which forms a portion of the novel controlling mechanism of the present application. This valve 13 is designed to cooperate with a pilot burner which is designated by the reference numeral 14 to form a safety pilot arrangement. The pilot burner 14 is supplied with fuel from the line 11 through a pipe 15. As indicated from the previous description, the function of the device is such that when the pilot burner 14 is not lighted, the valve 13 is closed, thus cutting off a supply of fuel to the main burner. It will be obvious that if desired the valve 13 can be placed on the other side of the main control valve 12 with the connection of pipe 15 to the fuel line 11 interposed between the two valves so that when valve 13 is closed a supply of fuel to both the main burner and the pilot burner is cut off. Inasmuch as either form can be employed, the form shown in the drawing has been selected for illustration because of its greater ease of illustration.

Referring first to Figure 2, the valve of the present invention is shown as comprising a valve body 20 having the usual inlet and outlet connections 21 and 22. The valve body 20 is also provided with the usual transverse partition wall 23, which is provided with an opening therethrough providing a valve seat 24. A valve disc 25 which is provided with suitable valve facing material 26 is adapted to seat on the valve seat 24. The facing material 26 is held against the main portion of valve disc 25 by a washer 27 and a nut 28 which serves to clamp the various members of the valve disc arrangement together between the nut and a shoulder 29 on a valve stem 30. The valve body is closed at the top by a cap 32 which is secured to the valve body by a screw threaded flanged collar 33.

Secured to the interior of the valve body by screws 36 or other suitable fastening means is a U-shaped bracket 37. Pivotally supported by the bracket 37 is a bell crank lever 38. One arm of the bell crank lever 38 consists of a U-shaped portion 39, the front base leg of which is inclined as indicated at 40. One leg of the U-shaped arm 39 extends upwardly to provide the other arm 41 of the bell crank lever.

Pivotally connected to the foremost portion of the arm 39 of bell crank lever 38 through a pivot pin 44 is a second bell crank lever 45. This lever consists of an arm 46 best shown in Figures 3 and 4 which consists of two side portions 47 connected by a cross-member 48. A second arm 49 consists of a single member of angular shape as shown most clearly in Figures 3 and 4. The two spaced legs 47 of the arm 46 of bell crank lever 45 are provided with pins extending into slots 51 in the valve stem 30.

Secured to the cap 32 is a rod 55 on which the valve stem 30 is slidably mounted. A spring 56 bears against the under side of the cap and the upper side of valve 30 and urges the valve to closed position.

Extending through the valve body is a stem 60 of a manual valve operator for resetting the valve. This operator is provided at its outermost end 75 when the other elements are in the position

with a knob 61 which bears against a boss projecting from the valve housing. The stem 60 of the operator is provided with a collar 62 and a spring 63 is interposed between the inner wall of the valve housing and the collar 62, which spring serves to bias the operator into its innermost position. Also resting against the collar 62 is the uppermost end of the arm 41 of bell crank lever 38. It will be readily seen that withdrawal of the operator against the action of spring 63 will rotate the lever 38 in a counterclockwise direction.

Slidably mounted in a sleeve 65 threaded into the valve housing, is a pin 66 which pin is biased inwardly by a spring 67 as will be more fully explained later. This pin 66 constitutes the means for holding the valve open as will be clear from a subsequent explanation of the operation of the device. Secured to the cap 32 is a leaf spring member 70 which projects into the path of movement of the arm 49 of bell crank lever 45 under certain conditions.

In order to more clearly understand the function of the apparatus to be subsequently described the operation of the portion of the apparatus which has been just described previously will now be set forth. With the elements in the position shown in Figure 2, the pin 66 does not extend into valve housing of Figure 2, being in the position assumed when the pilot is extinguished. If the knob 61 of the manually operated reset mechanism is withdrawn causing collar 62 to move to the left, bell crank lever 38 will be rotated in a counter-clockwise direction bringing the lever substantially to the position shown in Figure 4. In this figure the pin 66 is shown as projecting into the path of the foremost portion 40 of the arm 39 of bell crank lever 38, the position assumed when the pilot is ignited. Under these conditions the bell crank lever 40 is held against return movement. It will also be noted that rotation of the bell crank lever 38 in a counter-clockwise direction has caused rotation of bell crank lever 45 about the pivotal connection provided by pins of legs 47 moving in slots 51 so as to bring the upwardly extending arm 49 of bell crank lever 45 into engagement with the end of stem 60 of the manual operator. It will be noted, however, that in spite of the fact that the manual operator 61 is fully withdrawn the valve 50 25 remains in engagement with the valve seat 24.

Under the conditions shown in Figure 4, if the manual operator is now released the spring 63 is effective to force the stem 60 to the right rotating the bell crank lever 45 in a clockwise direction about the pivot pin 44. This action causes the arm 46 of lever 45 to raise the valve stem 30 against the biasing action of spring 56 and consequently to move the valve away from the seat. The various elements will then be in the position shown in Figure 5. It will be noted that during the movement following from the release of the knob 61 of the manual operator, the upwardly extending arm 38 of bell crank lever 49 has ridden over leaf spring 70, snapping over the end thereof, so that leaf spring 70 is effective to prevent counterclockwise rotation of bell crank lever 45 about pivot pin 44.

The action just described is that which takes place when the withdrawal of the knob 61 of the manual reset mechanism is made at a time when the pilot is burning and the pin 66 constituting the holding device of the valve is in the position assumed under such conditions. If, however, pin 66 is not in its foremost position 70 75 when the other elements are in the position

shown in Figure 4, the releasing of knob 61 merely results in bell crank lever 38 rotating in a clockwise direction back to the position shown in Figure 2, with the bell crank lever 45 pivoting about the pins in the slots 51 rather than about pin 44. It will thus be seen that under these conditions the operation of the resetting mechanism does not at any time change the position of the valve. In other words, the resetting device can be operated as often as desired without altering the relative position of the valve and valve seat. In this way the mechanism overcomes the disadvantages of the prior device wherein the operation of the reset mechanism momentarily opens the valve.

It will be further noted that with the elements in the position shown in Figure 5, the withdrawal of knob 61 will not permit the valve to move to closed position. This is due to the presence of the leaf spring 70 which, as previously explained, is effective to prevent counterclockwise rotation of bell crank lever 45. If this leaf spring 70 were not provided, withdrawal of knob 61 would permit bell crank lever 45 to rotate in a counterclockwise direction permitting the valve to close until the knob 61 is again released. This would have the disadvantage that in the event that knob 61 is accidentally pulled out while the burner is in operation, the main burner would be extinguished. If while the knob is held out, the pilot burner is extinguished, both burners will then be extinguished. The subsequent release of knob 61 would then permit unignited gas to be admitted to the furnace until the thermostatic element associated with the pilot burner had cooled off sufficiently to withdraw the pin 66 to enable the valve to close. With the present arrangement, however, it is impossible to close the valve even momentarily after the same is opened so that the gas will continue to flow through the main burner and in the event of the pilot burner being extinguished, the main burner will continue to operate until the pilot burner has cooled down sufficiently to withdraw the pin 66 and cause the immediate closing of the valve 25.

In the previous description of the apparatus it was assumed that some means was provided for moving pin 66 against the action of spring 67 whenever the pilot burner was extinguished. One such means will now be described.

Referring to Figure 6, the pilot burner 14 is shown as comprising a burner tube 75 having an opening 76 adjacent the upper end thereof and an elongated slot 77 communicating therewith. At the lower end of the burner tube 75 an opening 79 is provided for the admission of air while extending into the lower end of the burner tube is a nozzle 80 which admits to the burner the gas flowing therethrough by pipe 15. A member 82 serves to couple pipe 15 with the burner tube 75. This member further serves as the bracket for a bell crank lever 83 which is pivoted thereto at 81. Bell crank lever 83 comprises two arms of bimetal material 84 and 85 which are both secured to a common pivotally mounted member 86. The uppermost end of bimetallic element 84 is bent substantially horizontally at 88 and engages the burner tube 75. As best shown in Figure 7, this portion 88 is provided with an opening 89 to prevent interruption of the flame issuing from the slot 77. Member 82 is provided on the side opposite to that which lever 83 is pivoted with the large portion 90 through which extends an aperture. Extending through this aperture and secured to member 75

82 by flaring is a flexible tube 91. This tube houses a chain 92 or other flexible member which is connected to a threaded stem 93. This stem extends through an opening in the bimetallic element 85 and is provided with nuts 94 which abut the bimetallic element.

The device is shown in Figure 6 in the position assumed when the pilot burner is ignited. In this position, the bimetallic element 84 is bowed inwardly due to the heat of the pilot burner flame. At the same time, the bimetallic element 85 is very slightly deflected upwardly due to the heat indirectly transmitted to the same through the bimetallic element 84. Due to the relatively greater bowing of bimetallic element 84, however, the stem 93 will be in its lowermost position, the cold position of bell crank lever 83 being indicated in dotted lines.

Due to the fact that the high expansion side of element 84 is adjacent the low expansion side of element 85 any bowing in these two elements caused by changes in ambient temperature will compensate each other so that any tendency for the outer end of bimetallic element 85 to be lowered as a result of element 84 being bowed inwardly by increase in the ambient temperature will be compensated by the outer end of element 85 moving upwardly as a result of that element being deflected upwardly as a result of being exposed to the same ambient temperature. In this manner it is assured that any movement imparted to the flexible chain 92 by reason of deflection of the bimetal element will be due to some change in temperature which affects element 84 more than element 85 and which would arise only by reason of the pilot being ignited.

Referring again to Figure 5, it will be noted that the outermost portion of pin 66 extends through a bushing 98 which is threaded into a sleeve member 65. This bushing serves to guide the path of pin 66 and at the same time serves to couple the other end of tubing 91 to the sleeve 65. As will be apparent from this figure the other end of flexible chain 92 is connected to pin 66 through a coupling member 99. It will thus be seen that at any upward movement imparted to stem 93 by reason of the pilot flame being extinguished and the thermostatic element cooling off, will cause flexible chain 92 to pull member 66 outwardly against the action of spring 67. Withdrawal of pin 66 will permit the bell crank lever 38 to rotate in a counter-clockwise direction permitting the valve to close.

It will thus be seen that I have provided a novel arrangement for actuating the holding means of the valve mechanism in response to the absence or presence of the pilot flame. This means is moreover free from the effect of ambient temperature so that there is no danger of the safety pilot mechanism permitting the valve to be opened in the event of an extremely hot ambient temperature such as may exist in a motor room under some conditions.

In Figures 8 and 9 there is shown a modified form of the invention wherein the holding means for the valve is actuated by an electro-magnet which in turn is energized by a thermo-couple, the hot junction of which is located adjacent the pilot burner. Referring first to Figure 8, there is shown a burner control system wherein the controlling mechanism of the space is employed. A burner is designated by the reference numeral 110 and is supplied with fuel through the pipe 111 connected to a gas supply. Interposed in the pipe 111 is a main controlling valve 112, which corresponds in

function to the valve 12 of Figure 1. Corresponding to valve 13 of Figure 1 is valve 113 of Figure 8 which valve functions to interrupt the supply of fuel to the burner in the event the pilot burner should be extinguished. The pilot burner is designated by the reference numeral 114 and is supplied with fuel through a pipe 115. A thermocouple which energizes the electro-magnet referred to as operating the holding means is generally designated by the reference numeral 116 and is shown located in the flame of the pilot burner 114.

In Figure 9 the structure of the valve and the actuating mechanism for the holding means is shown. In this figure as well as in Figure 8, the elements corresponding to those shown in Figure 2 are given a reference character 100 higher than the number of the corresponding element in Figures 1 to 5. Thus the valve comprises a valve body 120 having inlet and outlet connections 121 and 122, the valve body being provided with a transverse partition 123 which is connected to the valve seat 124. A valve disc is designated by the reference numeral 125 and is provided with valve facing material 126 which is held in engagement with the valve disc 125 by a washer 127 and a nut 128 which serves to clamp the members against a collar 129 of a valve stem 130 in a manner similar to that described in connection with Figures 2 to 5. As in the previous species, the valve body is closed by a valve cap 132 which is held in place by a screw threaded flanged collar 133.

Secured to the valve body 120 is a U-shaped bracket 131 and pivoted to this bracket is a bell crank lever 138. Pivoted to bell crank lever 138 through a pivot pin 144 is a second bell crank lever 145. The structure and relation of members 137, 138 and 145 is exactly the same as that of members 37, 38 and 45 of Figure 2 so that a further detailed explanation of these members is deemed unnecessary in connection with this figure.

As in the preceding species, a stem 155 is secured to the cap 132 of the valve housing and the stem 130 is slidably mounted on downwardly extending stem 155. A spring 156 bears against the cap 132 at its upper end and against the end of the valve stem 130 at its lower end and serves to bias valve stem 130 to a closed position.

The manually operable reset device consists of a stem 160 and a knob 161, the stem 160 having a shoulder 162 against which bears a spring 163. All of these parts are similar to the corresponding parts of the previous species. A pin 166 extends into the valve casing into the path of the forward portion of bell crank lever 138 in a manner similar to the method in which pin 166 contacted with bell crank lever 38 in the previous species.

A leaf spring 170 is secured to the wall of the valve housing 120 through a bracket 172. This leaf spring 170 cooperates with member 145 in the manner similar to that which the corresponding elements of the previous species cooperated.

The structure described so far in connection with Figure 9 is substantially the same as that shown in Figures 2 to 5. As previously indicated, however, the essential difference between the previously described species and the present species is in the means for actuating the holding pin 166. As previously indicated, this pin in this species is actuated by an electro-magnet which is energized by a thermo-couple 116. The electro-magnet is housed in a casing member 175 of non-magnetic material, which is secured to valve casing 120 by screws 176 or other suitable fastening medium.

The electro-magnet referred to consists generally of a U-shaped core member 177 and a cooperating armature member 178. The core member 177 is fastened to a disc 183 which disc is in turn secured to the casing 175. The armature 178 is held in a clip 179 which is connected to a crossbar 180 through a strain release connection consisting of a pin 181 and a spring 182 interposed between the crossbar 180 and the clip 179. The crossbar 180 is connected to the two side portions 190 and 191 of a yoke member comprising said side portions 190 and 191 and the transverse bar 192. The pin 166 is connected to the transverse bar 192. A spring 193 bears at one end against the bar 192 and at the other end against a closure plate 194 which is in turn secured to casing 120 and serves to bias the armature away from the core member 177. The two side portions 190 and 191 of the yoke extend through tubular guiding sleeves 195 and 196.

In Figure 10 the clip portion 179 is shown in somewhat greater detail. It will be noted from this figure that the crossbar 180 is provided with side members 198 which serve to guide the clip 179 and consequently the armature 178. The side flanges 198 served to prevent turning of the armature 178.

A thermo-couple is generally indicated by the reference numeral 116. This thermo-couple comprises the usual elements 200 and 201 of different thermo-electric characteristics which are joined at 202 to provide the "hot junction" of the thermo-couple. While the materials employed for elements 200 and 201 may be any material having suitable thermo-couple characteristics, I have found it desirable to employ an inner member of "constantan," an alloy comprising approximately 50% nickel and 50% copper, and an outer member 200 of stainless steel. The stainless steel employed may be any suitable stainless steel capable of adequately resisting the heat of the pilot burner flame. The inner member 201 is secured to a conductor 203 which is insulated as at 204. The outer member 200 is connected to a copper reducing sleeve 205 which in turn is connected to a copper tubing 206. The copper tubing 206 is electrically connected through a sleeve 207 with the casing 175. The inner conductor 203 is connected to a conductor 209 through a coupling sleeve 210 which is suitably insulated from sleeve 207 by insulating member 211. The conductor 209 forms the winding of the electro-magnet. The other end of the conductor 209 is electrically secured to the casing 175 at 212.

In order for the extremely small electro-motive force which is generated by the difference in temperature between the hot junction 202 and the cold junction, to produce a sufficient holding action in the electro-magnet, it is necessary that the resistance of the circuit energized by the thermo-couple be extremely low. In order for this to be true it is necessary that conductors 204 and 209, copper tubing 206 and sleeve 207, to be of relatively large size so as to offer little resistance to the flow of current.

While the current generated by the thermo-couple is sufficient to energize the magnet sufficiently to hold the armature 178 into engagement with core 177 against the action of spring 193, it is not sufficient to so energize the magnet as to cause armature 178 to be pulled into engagement with core 177. Consequently it is necessary that some means be provided for moving 75 the armature 178 into engagement with the core

177. A third bell crank lever 215 is provided for this purpose. This bell crank lever consists of a horizontally extending arm 216 and a substantially vertically extending arm 217. The horizontally extending arm 216 lies in the path of movement of pivot pin 144, while the vertically extending arm 217 of bell crank lever 215 is adapted to engage a collar 219 secured to pin 166. It will be more or less apparent that upward movement of pin 144 will cause the bell crank lever 215 to move the pin 166 inwardly and to thus move armature 178 against the core 177 of the electro-magnet.

The operation of the device so far as the valve structure is concerned is substantially similar to that described in connection with Figures 2 to 5. Thus upon knob 161 being pulled to the left, with the valve in closed position, the bell crank lever 138 is rocked in a counterclockwise direction. This movement is carried sufficiently far that pin 144 is effective to rock bell crank lever 215 so far to the right as to pull pin 166 inwardly sufficient to cause engagement of armature 178 with core 177. It will be noted in this connection that in the position shown in the drawing wherein the pin 166 is in its holding position, the arm 217 is not in engagement with the collar 219 on pin 166 nor is the lever 215 resting in engagement with the pivot pin 144. The reason for this is that it is necessary that, if the armature is not held in engagement with core 177 when so moved, the arm 217 of bell crank lever 215 will have moved sufficiently to the right by the time that lever 138 would have engaged the pin, to permit the spring 193 to withdraw the pin sufficiently to permit continued clockwise movement of bell crank lever 138. In other words, unless the armature 178 is held by the core 177 the action will be as follows: The bell crank lever 215 will not act appreciably upon pin 166 until the bell crank lever 138 has cleared the end of pin 166 whereupon further outward movement of arm 161 rotates bell crank lever 215 through the action of pin 144 thereon and causes pin 166 to be moved inwardly sufficient to cause engagement of the armature and core. Upon the knob being released, by the time that bell crank lever 138 has reached a point where it would engage pin 166 if held inwardly, the pin has moved outwardly sufficiently by reason of spring 193 so that lever 138 continues to rotate in a clockwise direction. As a result, the arrangement described permits the movement of armature 178 into engagement with core 177 while at the same time keeping it out of the path of movement of bell crank lever 138 unless the electro-magnet is energized.

If the magnet is energized pin 166 will be held in its innermost position and any action will be exactly the same as described in connection with previous species. In other words, the bell crank lever 138 will be prevented from rotating in a clockwise direction back to its original position so that the pivot point of pivot pin 144 remains stationary. The action of the stem 160 against the bell crank lever 145 through spring 163 will cause the lever 145 to rotate in a clockwise direction raising valve stem 130 against the action of biasing spring 156, thus opening the valve. Furthermore, the leaf spring 170 snaps back of the bell crank lever 145 in the same manner as leaf spring 70 engaged bell crank lever 45, to prevent counter-clockwise movement of bell crank lever 145 in the event of the accidental operation of the resetting mechanism. Thus, as in the previously

described species, it is impossible to open the valve unless the pilot flame is ignited and after the valve has been opened it is impossible to close the valve unless the pilot burner is extinguished.

6 It will be seen that I have provided a safety pilot arrangement wherein it is impossible by means of manual resetting means to open the main valve unless the pilot is ignited and that further it is impossible to close the valve after the 10 same has been opened except by extinguishing the pilot. While I have described the safety pilot mechanism in connection with a valve, it is to be understood that my invention is not to be so limited. The valve and valve seat 24 can be replaced by any other cooperating relatively movable members which function to either directly control the operation of the main valve or in some manner to control the operation of the main valve. Furthermore the relatively movable members 15 constituted by the valve and valve seat in the illustrated species could just as well be the relatively movable members of any desired controlling mechanism. It is to be understood that the 20 species shown in the drawing and described previously are for purposes of illustration only and that my invention is to be limited only by the 25 scope of the appended claims.

I claim as my invention:

1. In combination, a valve, means biasing said 30 valve to a closed position, a linkage mechanism connected to said valve, holding means comprising a condition responsive device operative upon the existence of a predetermined condition to cooperate with an element of said linkage mechanism to hold said valve in open position, and actuating means for moving said element into cooperative relationship with said holding means without moving said valve from its closed position, and upon said holding means being effective 35 for cooperating with said linkage mechanism to move said valve to open position.

2. In combination, a valve, means biasing said 40 valve to a closed position, a linkage mechanism connected to said valve, holding means comprising a condition responsive device operative upon the existence of a predetermined condition to cooperate with an element of said linkage mechanism to hold said valve in open position, actuating means for moving said element into cooperative 45 relationship with said holding means without moving said valve from its closed position, and upon said holding means being effective for cooperating with said linkage mechanism to move said valve to open position, and means to prevent 50 said valve from being moved to closed position, when in open position, by operation of said actuating means.

3. In combination, a valve, means biasing said 55 valve to closed position, a lever pivotally connected thereto, a second lever, a fixed pivotal mounting therefor, a pivotal connection between said first and second levers at a point spaced from the pivotal connection of said first lever to said valve, holding means, means responsive to a condition 60 whose presence is desirable prior to the opening of said valve for retaining said holding means in an operative position when said condition exists, and a reciprocable manual operator biased to one extreme position and operative when moved against its bias to substantially its other extreme position to change the angular position of said second lever and bring it into cooperative relationship with said holding means, said change in 65 angular position of said second lever being effective to move said first lever about its pivotal con-

nection to said valve into the path of movement of said operator, said operator being operative upon return movement thereof by said biasing means and upon return movement of said second lever being prevented by said holding means to move said first lever and through such movement to move said valve to open position.

4. In combination, a valve, means biasing said valve to closed position, a lever pivotally connected thereto, a second lever, a fixed pivotal mounting therefor, a pivotal connection between said first and second levers at a point spaced from the pivotal connection of said first lever to said valve, holding means, an electromagnet and a thermocouple controlling the energization thereof for retaining said holding means in an operative position, and a reciprocable manual operator biased to one extreme position and operative when moved against its bias to substantially its other extreme position to change the angular position of said second lever and bring it into cooperative relationship with said holding means, said change in angular position of said second lever being effective to move said first lever about its pivotal connection to said valve into the path of movement of said operator, said operator being operative upon return movement thereof by said biasing means and upon return movement of said lever being prevented by said holding means to move said first lever and through such movement to move said valve to open position.

5. In combination, a valve, means biasing said valve to closed position, a lever pivotally connected thereto, a second lever, a fixed pivotal mounting therefor, a pivotal connection between said first and second levers at a point spaced from the pivotal connection of said first lever to said valve, holding means, means including a member distortable with changes in temperatures connected to said holding means and effective to cause said holding means to assume an operative position when said member is heated above a predetermined value, and a reciprocable manual operator biased to one extreme position and operative when moved against its bias to substantially its other extreme position to change the angular position of said second lever and bring it into cooperative relationship with said holding means, said change in angular position of said second lever being effective to move said first lever about its pivotal connection to said valve into the path of movement of said operator, said operator being operative upon return movement thereof by said biasing means and upon return movement of said second lever being prevented by said holding means to move said first lever and through such movement to move said valve to open position.

6. In a fuel burner control system, a main burner, means controlling the flow of fuel to said main burner comprising two elements movable with respect to each other and effective in a first relative position to prevent fuel being supplied to the burner and in a second position to permit fuel being supplied to the burner, a reciprocable operator movable between a first normal position and a second position, a pilot burner, holding means, and means responsive to the presence of ignition of said pilot burner to render said holding means operative, mechanism connected to said control elements and adapted to cooperate with said holding means, said operator being effective upon movement thereof from said first to said second position to move said mechanism without affecting the relative position of said

control elements into cooperative relationship with said holding means, said mechanism being operative upon said holding means being effective as the result of the pilot burner being ignited and upon return movement of said operator to its first normal position to cause said control elements to move relative to each other to assume their second relative position wherein they permit fuel to be supplied to said main burner, said operator being ineffective to move said elements from said second relative position.

7. In a fuel burner control system, a main burner, means controlling the flow of fuel to said main burner comprising two elements movable with respect to each other and effective in a first relative position to prevent fuel being supplied to the burner and in a second position to permit fuel being supplied to the burner, a reciprocable operator movable between a first normal position and a second position, a pilot burner, electromagnetic holding means and a thermocouple having its hot junction located adjacent said pilot burner to cause energization of said holding means when said pilot burner is ignited, mechanism connected to said control elements and adapted to cooperate with said holding means, said operator being effective upon movement thereof from said first to said second position to move said mechanism without affecting the relative position of said control elements into cooperative relationship with said holding means, said mechanism being operative upon said holding means being effective as the result of the pilot burner being ignited and upon return movement of said operator to its first normal position to cause said control elements to move relative to each other to assume their second relative position wherein they permit fuel to be supplied to said main burner, said operator being ineffective to move said elements from said second relative position.

8. In combination, control means comprising two elements movable with respect to each other for performing a control function, means biasing said members to a first position, holding means comprising an electromagnet, a movable armature, and a thermocouple connected to said electromagnet and operative when its hot junction is heated to energize said electromagnet therewith but insufficiently to move said armature into such engagement, mechanism connected to said control means and adapted to cooperate with said holding means, reciprocable actuating means effective when moved in one direction to move said mechanism and said armature into a position in which said armature engages said electromagnet without moving said control elements relative to each other, said mechanism being effective upon return movement of said actuating means to move said control elements relative to each other to a second relative position if said electromagnet is sufficiently energized to hold said armature.

9. In a fuel burner control system, a main burner, means controlling the flow of fuel to said main burner comprising two elements movable with respect to each other and effective in a first relative position to prevent fuel being supplied to the burner and in a second relative position to permit fuel being supplied to the burner, a reciprocable operator movable between a first normal position and a second position, igniting means for said main burner, holding means comprising an electromagnet, a movable armature, and a thermocouple having its hot junction

located adjacent said igniting means and connected to said electromagnet, said thermocouple being effective when its hot junction is heated to energize said electromagnet sufficiently to hold said armature in engagement therewith but insufficiently to move said armature into such engagement, mechanism connected to said control means and adapted to cooperate with said holding means, reciprocal actuating means effective when moved in one direction to move said mechanism and said armature into a position in which said armature engages said electromagnet without moving said control elements relative to each other, said mechanism being effective upon return movement of said actuating means to move said control elements relative to each other to said second relative position if said electromagnet is sufficiently energized to hold said armature.

10. In a fuel burner control system, a main burner, means controlling the flow of fuel to said main burner comprising two elements movable with respect to each other and effective in a first relative position to prevent fuel being supplied to the burner and in a second position to permit fuel being supplied to the burner, a reciprocal operator movable between a first normal position and a second position, electromagnetic holding means comprising two relatively movable elements, one an armature and the other an electromagnet, a thermo-couple, means for producing a pilot flame adjacent the hot junction of said thermo-couple, said thermo-couple being connected to said electromagnet so as to cause energization of said electromagnet when said pilot flame is present, means operatively connected to said control elements and adapted to cooperate with one of said two relatively movable elements of the holding means, said operator being effective upon movement thereof from said first to said second position to move said two elements of said holding means into engagement without affecting the relative position of said control elements, and said means operatively connected to said control elements being operative upon said elements of said holding means being retained in engagement as a result of the existence of the pilot flame and upon return movement of said operator to its first normal position to cause said control elements to move relative to each other to assume their second relative position wherein they permit fuel to be supplied to said main burner.

11. In combination, a main fluid fuel burner, a pilot burner, means controlling the flow of fuel to said main burner and biased to a flow preventing position, means for holding said controlling means in a flow permitting position, said holding means including an armature and an electromagnet, a thermo-couple connected to said electromagnet and having its hot junction exposed to said pilot burner for energizing the electromagnet sufficiently to hold said armature in engagement therewith but insufficiently to move said armature into such engagement, a reciprocal reset member, means operative upon movement of said reset member in one direction to move said armature into engagement with said electromagnet while maintaining said controlling means in a condition preventing fuel flow to the burner, and means operative upon return movement of said reset member to its original position and upon said electromagnet retaining said armature in engagement therewith to move said

controlling means to said flow permitting position.

12. In combination, a fluid supply conduit, a valve for controlling the supply of fluid through said conduit, a movable armature operable to control said valve, an electromagnet for said armature, a thermo-couple connected to said electromagnet for energizing said electromagnet, means for resetting said armature with respect to said electromagnet, and means operable to shut off the supply of fluid through said conduit during the resetting operation.

13. In combination, a main burner, a fuel supply line for said burner, a pilot burner for said main burner, valve means in said fuel supply line for controlling the supply of fuel through said line, a movable armature operable to control said valve, an electromagnet for said armature, a thermo-couple in proximity to the pilot burner and connected to said electromagnet for energizing said electromagnet by the heat of the pilot burner, means for resetting said armature with respect to said electromagnet, and means operable to shut off the supply of fuel through said fuel supply line during the resetting operation.

14. In a device of the character described, in combination, a controlling member having an operative position and a safety position, latch means for holding said controlling member in operative position, an electromagnet, an armature for said electromagnet which, by movement to retracted position, releases said latch means for movement of said controlling member to safety position, and reset means for actuating said armature to attracted position and in the actuation of the armature to attracted position being operative to move said latch means to position to pick up said controlling member for actuation thereof to operative position.

15. In a condition control apparatus: a device to be actuated, an actuating member, means interconnecting said device and said member and including a plurality of continuously-interconnected and normally relatively-movable elements, and means responsive to a condition of said apparatus which must be maintained during the entire period of operation thereof for so limiting the relative movement of said elements that actuation of said member effects actuation of said device only while said required condition exists.

16. In a condition control apparatus: a device to be actuated, an actuating member, means interconnecting said device and said member and including a plurality of continuously-interengaged and normally relatively-movable driving elements, and means responsive to a condition of said apparatus which must be maintained during the entire period of operation thereof for so conditioning said elements that actuation of said member effects actuation of said device only while said required condition exists.

17. In a condition control apparatus: a device to be actuated, an actuating member, means interconnecting said device and said member and including a plurality of continuously-interengaged and normally relatively-movable driving elements, and means responsive to a condition of said apparatus which must be maintained during the entire period of operation thereof for so limiting the relative movement of one of said elements that actuation of said member effects actuation of said device only while said required condition exists.

18. In a condition control apparatus: a device to be actuated, an actuating member, means in-

terconnecting said device and said member and including a plurality of continuously-interconnected and normally relatively-movable elements, and means responsive to a condition of said apparatus which must be maintained during the entire period of operation thereof and effective in the initial actuation of said member to so condition said elements that subsequent actuation of said member effects actuation of said device only while said required condition exists.

19. In a condition control apparatus: a device to be actuated, an actuating member; a plurality of continuously-interconnected elements interconnecting said device and said member; said elements being normally so relatively movable that actuation of said device by said member is prevented; means temporarily moved, by the initial actuation of said member, to a position wherein relative movement of said elements is limited; electromagnetic means for maintaining said last-named means in said position so that subsequent actuation of said member effects actuation of said device; and means responsive to a condition of said apparatus which must be maintained during the entire period of operation thereof for controlling the energization of said electromagnetic means.

20. In a condition control apparatus: a device to be actuated; an actuating member; a plurality of continuously-interconnected and normally relatively movable elements so interconnecting said member and said device that only when the relative movement of at least one of said elements is limited does actuation of said member effect actuation of said device; means, including a movable arm, for limiting movement of said element when said arm is in a predetermined position; means operated by initial actuation of said member, without effecting actuation of said device, for moving said arm to said position; and means, responsive to a condition of said apparatus which must be maintained during the entire period of operation thereof, for maintaining said arm in said position, so that subsequent actuation of said member then effects actuation of said device.

21. An electrically operable safety device for controlling flow of fluid fuel to a burner, comprising, a valve body having a passage therethrough, a valve for controlling the flow of fluid through said passage, resettable holding means operable to hold said valve open, said holding means including an electromagnet and an armature, said electromagnet having a winding of low resistance so that said electromagnet is capable of being operatively energized by a thermo-couple means exposed to a burner flame, means for resetting said holding means, and means operatively cooperating with said resetting means and valve for maintaining the valve closed during the resetting operation.

22. An electrically operable safety device for controlling flow of fluid fuel to a burner, comprising, a valve body having a passage therethrough, a valve for controlling the flow of fluid through said passage, resettable holding means operable to control said valve in a position in which fluid is permitted to flow through said passage, said holding means including an electromagnet and an armature, said electromagnet having a winding of low resistance so that said electromagnet is capable of being operatively energized by a thermo-couple means exposed to a burner flame, means for resetting said holding means, and means operatively cooperating with said resetting means and valve for preventing

the flow of fluid through said passage during the resetting operation.

23. An electrically operable safety device for controlling flow of fuel to a burner, comprising, a control device movable between first and second positions, resettable holding means operable to hold said control device in its second position, said holding means including an electromagnet and an armature, thermo-couple means adapted to be exposed to a burner flame for energizing said electromagnet, means for resetting said holding means, and means operatively cooperating with said resetting means and said control device for maintaining said control device in its first position during the resetting operation.

24. An electrically operable safety device for controlling the flow of fuel to a burner, comprising, control mechanism for effecting first and second control actions, means biasing said control mechanism to effect its first control action, resettable holding means including an armature and an electromagnet for holding said control mechanism against its bias to effect its second control action when said electromagnet is energized to hold said armature in an attracted position, said holding means releasing said control mechanism to effect its first control action upon deenergization of said electromagnet, said electromagnet having a winding of low resistance so that said electromagnet is capable of being operatively energized by a thermo-couple means exposed to a burner flame, means for resetting said holding means to its holding position after deenergization of said electromagnet, and means operable as a part of the resetting operation to prevent said control mechanism from effecting its second control action during the resetting operation.

25. An electrically operable safety device for controlling the flow of fuel to a burner, comprising, control mechanism for effecting first and second control actions, means biasing said control mechanism to effect its first control action, resettable holding means including an armature and an electromagnet for holding said control mechanism against its bias to effect its second control action when said electromagnet is energized to hold said armature in an attracted position, said holding means releasing said control mechanism to effect its first control action upon deenergization of said electromagnet, thermo-couple means adapted to be exposed to a burner flame for energizing the electromagnet, means for resetting said holding means to its holding position after deenergization of said electromagnet, and means operable as a part of the resetting operation to prevent said control mechanism from effecting its second control action during the resetting operation.

26. An electrically operable safety device for controlling the flow of fuel to a burner, comprising, control mechanism for effecting first and second control actions, means biasing said control mechanism to effect its first control action, resettable holding means including an armature and an electromagnet for holding said control mechanism against its bias to effect its second control action when said electromagnet is energized to hold said armature in an attracted position, said holding means releasing said control mechanism to effect its first control action upon deenergization of said electromagnet, said electromagnet having a winding of low resistance so that said electromagnet is capable of being operatively energized by a thermo-couple means ex-

posed to a burner flame, means for resetting said holding means to its holding position, after deenergization of said electromagnet, means operable as a part of the resetting operation to prevent said control mechanism from effecting its second control action during the resetting operation, and means operable after the resetting operation has been completed to prevent operation of said control mechanism to effect its first control action upon again operating said reset means.

27. An electrically operable safety device for controlling the flow of fuel to a burner, comprising, a control device movable between operative and non-operative positions, means biasing said control device to its non-operative position, resettable holding means including an armature and an electromagnet for holding said control device in its operative position against its bias when said electromagnet is energized to hold said armature in an attracted position, said holding means releasing said control device for movement to non-operative position upon deenergization of said electromagnet, said electromagnet having a winding of low resistance so that said electromagnet is capable of being operatively energized by a thermo-couple means exposed to a burner flame, means for resetting said holding means to its holding position after deenergization

of said electromagnet, and means operable as a part of the resetting operation to maintain said control device in said non-operative position during the resetting operation.

CARL G. KRONMILLER.
